(57) **CLAIM**

The ornamental design for a coordinate input apparatus, as shown and described.

DESCRIPTION

FIG. 1 is a perspective view of a coordinate input apparatus showing my new design;

FIG. 2 is a front view of the coordinate input apparatus shown in FIG. 1;

FIG. 3 is a rear view of the coordinate input apparatus shown in FIG. 1;

FIG. 4 is a right side view of the coordinate input apparatus shown in FIG. 1, the left side view being mirror symmetrical thereto;

FIG. 5 is a top view of the coordinate input apparatus shown in FIG. 1; and,

FIG. 6 is a bottom view of the coordinate input apparatus shown in FIG. 1.

While the solid lines in the drawings form part of the claimed design, the solid lines provide written description of prospective embodiments that are not claimed when one or more of the solid lines are amended to broken lines.
